INVENTOR

William Ledyard Mitchell

John Barnes
ATTORNEY

UNITED STATES PATENT OFFICE.

WILLIAM LEDYARD MITCHELL, OF GROSSE POINTE FARMS, MICHIGAN.

AUXILIARY GASOLINE-SUPPLY DEVICE.

Application filed June 27, 1924. Serial No. 722,728.

To all whom it may concern:

Be it known that I, WILLIAM LEDYARD MITCHELL, a citizen of the United States, and resident of Grosse Pointe Farms, county 5 of Wayne, State of Michigan, have invented certain new and useful Improvements in Auxiliary Gasoline-Supply Devices, of which the following is a specification, reference being had to the accompanying drawings.

It is the primary object of my invention to provide an auxiliary gasoline supply device of the type wherein the gasoline supply line, which extends into the gasoline tank, is 15 crooked, or otherwise bent, at its lower end and is pivoted at its upper end, so that movement thereof will cause the extreme outer end of the lower portion to be either raised or lowered, as desired, with the result that 20 when raised a supply of gasoline in the bottom of tank is not accessible to the end of the feed line; whereas when it is lowered, such gasoline is accessible thereto.

It is a still further and primary object of 25 my invention to so position the operating lever which swings the pivoted feed line that when it is in position for lowering the end of the feed line it will be over the filler cap of the gasoline tank, so that the cap 30 may not be removed and additional fuel supplied to the tank until the lever is moved so as to move the end of the feed line to its elevated position.

With the above, and other objects, in view, 35 my invention consists in the arrangement, combination and construction of the various parts of my improved devices as described in the specification claimed in my claim and shown in the accompanying drawings, in which:

Fig. 1 is an elevation of a gasoline tank, partly in section, showing my improved device therein.

Fig. 2 is a top or plan view taken on line 45 2-2 of Fig. 1.

Fig. 3 is a sectional view taken on line 3-3 of Fig. 2.

Fig. 4 is a sectional view showing one modification of my improved device.

Fig. 5 is a sectional view showing another modification of my improved device.

I have shown a gasoline tank 5, having the customary filler cap 6 and filler neck 7 thereon.

The top of the gasoline tank is provided 55 with a slight elevation 8, which is interiorly

screw-threaded to receive the screw-threaded end 9 of a fitting having a hollow spherical top 10, in which is positioned a ball 11. The top portion of the hollow member 10 is 60 cut away as at 12 and the screw-threaded end 13 of a handle 14 is inserted therethrough into engagement with the ball 11. A gasoline supply pipe 15, having a crooked end 16, is extended into the gasoline 65 tank 5, and has its upper end secured as at 17 to ball 11.

The ball 11 is provided with a passageway 18, connected with the end of the feed line 15 and to a second feed line 17 secured to 70 the projection 18 on the outside of the member 10 by means of a screw-threaded connection 19.

With the above construction gasoline in the tank 5 is drawn through the outermost 75 end 20 of the feed line 15, the passageway 16 and the feed line 17, to the ordinary vacuum tank or other source used for drawing the gasoline from the tank. When the gasoline level becomes lower than the outermost 80 end 20 of the feed line, the lever 14 may be moved to the position shown in dotted lines in Fig. 1, with the result that the ball 11 pivots so as to move the feed line 15, as shown in dotted lines in Fig. 1, and lower 85 the outermost end 20 thereof to a lower level in the tank 5 and permit additional gasoline to be drawn through the feed line. When this is done it will be seen that the end of the lever 14 is positioned over the filler cap 90 6, so that the cap may not be removed and additional gasoline supplied to the tank 5 until the lever is moved upwardly to its normal position.

While I have here described and shown 95 the lever 14 as being positioned over the filler cap 6, I desire it to be understood that any position of the lever 14 which will draw attention to it when the filler cap is being removed, is within the scope of my invention and it is my intention that any claim 100 shall be construed accordingly.

In Fig. 4 I have shown a modification of my invention wherein a tubular fitting 21 is screw-threaded on the projection 22 of 105 the gasoline tank 5 and an elongated member 23 of corresponding formation is inserted therein, to which is attached the feed line 15 and the lever 14. A cap 24 is screwed into one end of the fitting 21 and has secured therein the feed line 17. A passage 110 25 is also provided in the member 23, con-

necting the feed lines 15 and 17 and movement of the lever 14 will swivel the member 23 so as to move the feed line 15 in the same manner as heretofore described.

5 In Fig. 5 I have shown a further modification wherein a fitting 26 is screw-threaded to a projection 27 on the gasoline tank 5, a ball 28 is provided in the upper end of the fitting 26 and a cap 29 is screw-threaded 10 to said upper end as at 30 to secure the ball 28 in place. The lever 14 is secured in the same manner to the ball 28, as is the feed line 15. The feed line 17 extends into the passageway 31 provided in the ball 28 and 15 is secured by screw-threading directly to the fitting 26. By extending the feed line 17 into the passageway 31 it becomes impossible to move the lever 14 so that the connection between the pasageway and the feed 20 line 17 shall become disconnected or closed. The extension of the feed line 17 into the movable elements may be followed in the other formations heretofore described with equal success.

25 It will thus be seen that I have described a cheap and economical manner of securing an auxiliary gasoline supply, as well as one which will prevent the careless motorist from neglecting to rearrange his reserve 30 or auxiliary supply after having used it when refilling his gasoline tank.

It is obvious that various changes may be made in the arrangement, combination and construction of various parts of my improved device without departing from the 35 spirit of my invention, and it is my intention to cover by my claim such changes as may be reasonably included within the scope thereof.

What I claim is:

40 In combination, a tank having a filler spout thereon, a member secured to said tank, a socket in said member, a movable member fitted in said socket, a passage in said movable member, a conduit in said tank 45 having one end connected in constantly open relation with said passage and fixed to said movable member, so as to be movable therewith, a second conduit connected with said first member and open to said passage and 50 first conduit, said first and second conduits being extended at different angles to said movable member, a handle connected with said movable member and adapted to move it on an axis concentric with the axis of said 55 second conduit, whereby said second conduit may be kept constantly open with said passage, said handle being so fashioned that it will overlie the said filler spout when moved in one direction.

WILLIAM LEDYARD MITCHELL.
